ICE CUBE TONGS

Alfred H. Ackerson, Glen Ellyn, Ill., assignor to
Utili-Tong, Inc., Chicago, Ill., a corporation of
Illinois

Application November 25, 1932, Serial No. 644,300

3 Claims. (Cl. 294—115)

This invention relates to tongs for use in picking up and handling ice cubes, sugar cubes, nuts, sweetmeats and other articles of similar nature and size.

The present invention is a continuation, in part, of my copending application, Serial No. 628,466, filed August 12, 1932, and, in its preferred embodiment, is directed to the provision of a miniature tongs comprising a tubular body portion having an actuating stem extending therethrough. The stem has a button secured at one end, and a grooved collar is suitably secured to the other end. The stem is capable of reciprocal movement within the body portion, and is maintained in position by a coiled spring encircling the stem and abutting against the button for normally holding the stem in raised position to maintain the jaws closed. Of course, it is to be understood that, if desired, the operation of the device may be reversed, so that the jaws are normally maintained opened, and are closed by the depressing of the button.

The tong members comprise a pair of pivotally mounted tines which are disposed at the lower end of the tubular body portion, and which have extending integral cam portions engaging in suitable recesses in the grooved collar for moving the tongs into open and closed position upon movement of the stem and collar. The tong members are pivotally engaged within a yoked collar secured over the end of the tubular body portion. The tongs have a relatively large ratio of movement with respect to the movement of the collar, because of the proximity of the pivots with respect to the grooved collar. The ends of the tongs are preferably sharply pointed, and the spring is of sufficient strength to force the ends to bite into the surface of the engaged article and to urge the tongs to closed position. An annular flange on the tubular body portion provides a grip for the fingers of the operator, and the enlarged head or button on the stem is engaged by the thumb or palm of the hand when it is desired to compress the spring to open the tongs.

A primary object of the present invention is the provision of a tongs of the class described which may be easily and economically constructed, and which is fool-proof when completely assembled. To accomplish this end, I preferably provide pressed fit of the flange member upon the tubular body portion, pressed fit of the spring seat within the body portion, and pressed fit of the yoked collar upon the end of the body portion. Also, the grooved collar and actuating but-

ton are both press fitted upon the reciprocal stem, and therefore cannot be disassembled when the device has been once assembled. Further, if desired, I provide bottle opening means secured upon the tubular body portion, preferably adjacent the lower end thereof, which may be press fitted thereon. This manner of securing the constituent parts of the device in assembled relation eliminates the use of threads, welding, knurling, or the like.

Another object of the invention is to provide a pair of pivotally mounted tong members having camming engagement with a movable collar, wherein the ratio of movement of the tongs with respect to the movement of the collar is relatively large.

A further object of the present invention is to provide a yoked support for pivoting the individual tong members, the yokes being formed as integral portions of a collar which is press fitted over the end of the body portion, and which yokes are engaged by hooked portions of the tong members. These yoke supports provide for rocking movement of the tong members thereabout, and eliminate the use of a bearing and pivot pin for assembling the tongs upon the tubular body portion.

Other objects and advantages of the present invention will appear more fully in connection with the following detailed description, which, together with the accompanying drawing, will disclose to those skilled in the art the particular construction and operation of a preferred form of the invention.

In the drawing:—
Figure 1 is a perspective view of the tongs, showing the manner in which they engage an ice cube, or similar article;

Figure 2 is an enlarged sectional elevational view of the tongs; and

Figure 3 is a sectional view taken substantially on the line 3—3 of Figure 2, looking in the direction indicated by the arrows.

Considering now in detail the drawing, the tongs comprise a tubular body portion 5, of equal cross section throughout, which body portion is adapted to receive a reciprocal stem member 6. The stem 6 is of substantially the same length as the body portion 5, and is provided at its upper end with an operating button 8, the button having a suitable recess and being press fitted over the end of the stem to secure it thereto. At its lower end the stem 6 is provided with a collar member 9, having an annular groove 10 formed

therein. This collar is also press fitted over the end of the stem 6.

Pressed over the tubular body portion, and secured at a convenient distance from the upper 5 end thereof, is an annular flange or finger piece 12, and disposed above and within the tubular body portion is a ring member 13 which serves as a seat for the coiled spring member 14 extending about the stem 6 and abutting against 10 the inner shoulder of the button 8. The flange 12 is engaged by the fingers of the operator for providing a grip upon the tongs when it is desired to depress the button 8 for actuating the tong members.

15 The grooved collar 10 is provided with a pair of diametrically opposed recesses 15 and 16, which are adapted to receive the cam ends 17 and 18 of the tines 20. These cam surfaces ride within the recesses 15 and 16 and the groove 10 20 of the collar 9, and are adapted to rock the tines about their yoke supports upon reciprocal movement of the collar 9 occasioned by depressing and releasing the button member 8.

The tines 20 are each provided with a hooked 25 portion 21 engaging about a yoked support 22 formed integrally with an annular collar 23 secured over the end of the tubular member 5. This collar is shown clearly in Figure 2. The yoke supports 22 comprise downwardly turned 30 lip portions having a longitudinally extending slot 24 formed therein, which receives the cam ends 17 and 18 and the hooked portions 21 of the tines 20 when the tines are assembled with respect to the tubular body portion 5 and the collar 10. These longitudinal slots 24 provide 35 for receiving the tine members and, after the tine members have had their cam portions engaged within the collar, the hooked portions 21 engage about the lower ends of the supports 22 40 to provide for a pivoted engagement therewith, allowing rocking of the tines about this point.

If desired, a bottle opener may be also provided upon the tongs, this bottle opener comprising a substantially channel shaped metal stamping 45 25 having the extending leg portions engaging about the tubular body portion 5, these leg portions being indicated at 26 and 27 in Figures 1 and 2. The stamping 25 is also provided with the extending tongue member 28, adapted to be placed over the cap of a bottle, and with the curved tongue member 29 adapted to be engaged under the lip of the cap for raising the same.

The tines 20 are of the shape shown generally in Fig. 2, and are provided with integral inwardly 55 extending tip portions 30 which are preferably sharply pointed, to bite into the surface of the article being gripped by the tongs, this particular feature being disclosed in Figure 1, in which the tongs are shown as engaging an ice cube 31.

60 In assembling the constituent parts of the device, the flange member 12 is first pressed downwardly over the body portion 5 to the position shown in Figure 2, this pressure of the flange tending to compress the body portion. The ring 65 13 is then forced downwardly into the interior of the body portion 5, the ring 13 preferably being of a diameter slightly in excess of the internal diameter of the body portion 5 to provide a pressed fit therein. This member 13 is forced 70 to a position directly above the flange member 12, and is held in this position by means of the pressed fit, cooperating with the internal compression occasioned by the engagement of the outer flange member 12, to remain in fixed position 75 within the body portion 5. The bottle open-

ing means 25 is then press fitted over the opposite end of the body portion 5 to a position such as shown, and the ring member 23 is then press fitted over the end of the body portion 5 and securely held in position therewith. The tine members 20 are then secured in the yoke supports 22 by passing the cam portions 17 and 18 and the hook portions 21 thereof through the slots 24 until the hook portions are so positioned as to drop down below the supports to provide the pivotal connection as shown in Figure 2. The stem 6, together with the collar member 9 which is press fitted thereon, is then inserted through the lower end of the body portion 5, and the oppositely disposed recesses 15 and 16 are disposed therein, providing the structure as shown in Figure 2.

The spring member 14 is then positioned about the stem 6 and passed downwardly into the body portion 5 until the lower end thereof engages the support 13. The button member 8 is then forced over the upper end of the stem 6, and bears against the upper end of the spring 14. The spring is thus compressed slightly by the button member 8 and tends to hold the button member 8, 100 together with the stem 6, in its upper limiting position, as determined by the flanged portion 32 of the collar 9.

In the operation of the device, the button 8 is depressed to spread the tong members 20 apart to receive the article being gripped. Release of the button 8 allows the spring 14 to force the stem 6 upwardly to close the tong members about the article, the pointed ends 30 biting into the surface of the article to secure a firm grip thereupon. It will be noted that the supports 22 for the tong members are positioned closely adjacent the cam portions 17 and 18 thereof, so that a relatively small movement of the cam portions will result in a greatly increased ratio of movement 115 of the tong ends 30. This ratio of movement, in the preferred embodiment of my invention, is approximately 25 to 1, although this may be varied, depending upon the use to which the device is put.

It is apparent that, because of the pressed fit 120 of the elements with respect to each other, that the device may be manufactured very economically, and may be assembled in a simple and rapid manner. Also, this pressed fit of the parts insures that there will be no altering or removal of 125 any of the elements after the device has once been assembled, and therefore renders the tongs fool-proof after assembly.

I do not intend to be limited to the exact details shown and described, but only insofar as defined by the scope and spirit of the appended 130 claims.

I claim:

1. In a tongs having a tubular body portion and a stem mounted for reciprocal movement therein, the combination of a grooved collar press fitted over the lower end of said stem, a second collar press fitted over the lower end of said body portion and having integral angularly extending yoke portions, tong members having cam portions and hook portions, said members being passed through said yoke portions to engage said cam portions in said grooved collar and to engage said hook portions about said yoke portions, and a spring member normally maintaining said stem in raised position to close said tongs.

2. In a tongs having a tubular body portion and a stem mounted for reciprocal movement therein, the combination of a grooved collar press fitted over the lower end of said stem and having

opposed recessed portions, a second collar press fitted over the lower end of said body portion and having integral angularly extending yoke portions, tong members having cam portions and hook portions, said tong members being passed through said yoke portions to engage said cam portions in said recessed portions of said grooved collar and to engage said hook portions about said yoke portions, and a spring member normally maintaining said stem in raised position to close said tongs.

5 3. In a tongs having a tubular body portion, a reciprocal stem mounted in said body portion, and a spring for normally maintaining said stem

in raised position, the method of providing a seat for said spring interiorly of said body portion, which comprises pressing an outwardly flanged member over said body portion, said member having a diameter such that the diameter of said body portion is constricted during said pressing operation, and pressing a seating ring into the interior of said body portion to a point adjacent to and above said flanged member, said ring being of a diameter slightly greater than the constricted diameter of said body portion to expand the same to its normal diameter during said second pressing operation.
